L. J. ROSE

MANICURING GAUGE

Filed July 5, 1923

INVENTOR

LAWRENCE J. ROSE,
James C. Hopkins, ATTORNEY.

UNITED STATES PATENT OFFICE.

LAWRENCE J. ROSE, OF ST. LOUIS, MISSOURI.

MANICURING GAUGE.

Application filed July 5, 1923. Serial No. 649,540.

To all whom it may concern:

Be it known that I, LAWRENCE J. ROSE, a citizen of the United States of America, residing at the city of St. Louis, in the State 5 of Missouri, have invented certain new and useful Improvements in Manicuring Gauges, of which the following is a specification, reference being had therein to the accompanying drawing.

10 My invention relates to a manicuring gauge and has for its object to provide a gauge arranged to fit any of several fingers of various sizes in position to permit the nail of that finger to extend through and 15 protrude from a slot in said gauge, for the purpose of holding the nail while said nail is being reduced, by any suitable manicuring tool, to an outline fixed by the contour of the slot.

20 *Drawings.*

In the drawings:—

Fig. 1 is a side elevation of a gauge embodying my invention.

25 Fig. 2 is a top plan view of the same.

Fig. 3 is an enlarged fragmental view in vertical longitudinal section of the same, taken on the line 3—3 of Fig. 2, and showing a finger in place therein.

30 Fig. 4 is a view similar to that of Fig. 3 but taken in cross-section on the line 4—4 of Fig. 1.

Description.

Preferably formed from a single sheet 5 of suitable material the gauge is of substan-

tially U-shape, contoured to receive the terminal of a finger, and having outwardly-bulged grooves 6 at its mouth contoured to fit the user's finger and to prevent the slipping of the finger while the gauge is in use. 40

The gauge-body is preferably tapering in form from end to end (see Fig. 2) and has a series of arcuate slots 7, whose inner mouths are slightly flared (see Fig. 3) and whose outer mouths are flattened to form a smooth 45 pair of ridges 8 between which the finger-nail projects, and which serve as a gauge to which the nail is to be trimmed as shown in Fig. 4.

The gauge may have but one or any desired 50 number of the slots 7 and may be of any desired size and form to accommodate various sizes of fingers.

The engagement of the depressions 6 with the opposite sides of the finger whose nail is 55 to be manicured serves to hold the gauge in place without assistance, thus enabling the user to manicure himself.

Claim.

I claim:—

A manicuring gauge formed from a single sheet of metal having a series of arcuate slots and a series of outwardly-bulged 65 grooves arranged in operative alignment with reference to said slots.

In testimony whereof I have hereunto affixed my signature.

LAWRENCE J. ROSE.
